Filed Aug. 7, 1958, Ser. No. 52,090

Term of patent 3½ years

(Cl. D45—19)

FIG. 1

Fig. 1 is a top plan view of a jewelry finding showing my new design.

Fig. 2 is a side elevational view of the same.

Fig. 3 is a front elevational view of the same.

The radiating lines on Fig. 1 are engraved, and the central stippled area represents a matte surface, both in contrast with a shiny beveled edge.

I claim:

The ornamental design for a jewelry finding, as shown and described.
